UNITED STATES PATENT OFFICE.

FRANK S. JONES, OF PHILADELPHIA, PENNSYLVANIA.

SLOTTING MACHINE.

Application filed May 1, 1920. Serial No. 378,146.

To all whom it may concern:

Be it known that I, FRANK S. JONES, a citizen of the United States, residing at Philadelphia, in the county of Philadelphia 5 and State of Pennsylvania, have invented certain new and useful Improvements in Slitting Machines, of which the following is a specification.

One object of my invention is to provide 10 an improved slitting machine, commonly known as a slitter, which will be so constructed as to render it more easy to control and operate than other slitters made prior to my invention.

Another object is to so make my improved 15 slitter that various feeds may be effected without requiring the change or application of gear wheels or the like.

A further object is to make my improved 20 machine of a greatly simplified construction and so that the parts will be durable and efficient in operation.

These objects, and other advantageous ends 25 which will be described hereinafter, I attain in the following manner, reference being had to the accompanying drawings in which

Figure 1 is a side elevation of a slitter having parts made in accordance with my invention,

Figure 2 is a fragmentary sectional plan view taken on the line 2—2 of Figure 4,

Figure 3 is a fragmentary sectional elevation taken on the line 3—3 of Figure 2,

Figure 4 is a fragmentary elevation of certain of the features shown in Figure 1 and 35 illustrated with the gear covers removed,

Figure 5 is an enlarged fragmentary elevation, partly in section, showing an improved suspension link which forms a part 40 of my invention,

Figure 6 is a detail face view of said suspension link,

Figure 7 is a top plan view of Figure 6, and

Figure 8 is a side elevation of Figure 6.

Referring to the drawings, 9 represents a base or bed of a slitter having slidably mounted thereon a carriage 10 which rotatably supports a circular work table 11; said work table having a movement transversely on the carriage 10 and also a rotatable movement in a manner well known in the construction of slitters; the detail of construction not being shown on the drawing; it being sufficient to state that the transverse movement to the table 11 is imparted due to

the rotation of a screw shaft 12 while the rotatable movement of the table 11 is imparted by a worm shaft 13. The longitudinal movement of the carriage 10 is imparted by means of a feed screw shaft 14 in the usual manner.

My invention includes means for effecting a rotation of either of the shafts 12 or 13 without requiring the changing of any gears or the removal or application of any gears, and this feature of my invention is carried out by the following mechanism and can be controlled by an operator from either side of the machine. A short shaft 15 is mounted in a bearing 16 and has a ratchet wheel 17 secured thereto at one end of the bearing 16. This ratchet wheel is intermittently rotated by means of a pawl 18 which is carried by a freely swinging arm 19 on the end of the shaft 15; said arm receiving movement from a rod or link 20 of a type usually employed on slitters for imparting an intermittent movement to a feed shaft; it being sufficient to say that this movement can be imparted to the rod from a rotatable cam or any other moving part on the machine. The shaft 15 has a clutch collar 21 thereon in alignment with another clutch collar 22 which is slidably keyed to a feed shaft 23 located at the side of the base 9; said feed shaft 23 being rotatably mounted in a bearing 24. A hollow shaft 25 extends entirely through the base from one side to the other and has secured thereon a clutch operating lever 26 which is in engagement with the clutch collar 22.

Hand levers 27 and 28 are secured to the opposite ends of the hollow shaft 25 so that said hand levers are on opposite sides of the machine as clearly shown in Figures 2 and 3. Thus by moving either of the hand levers 27 or 28 the clutch collar 22 can be moved into clutching engagement with the clutch collar 21 and the movement of the shaft 15 will be imparted to the shaft 23. The shaft 23 has a bevel gear 29 slidably secured thereto; said bevel gear being formed of a sleeve having a bearing in an extension 31 of a bracket 32. The sleeve 30 has a collar or flange 33 which embraces the extension 31 so that there is no relative longitudinal movement between the bevel gear 29 and the bracket 32. The bracket 32 provides bearings for the shafts 12 and 13 and also for a bevel gear 34 which meshes with the bevel gear 29. A gear 35 is opera-

tively coupled to the bevel gear 34 and meshes with gear wheels 36 and 37; said gear wheels 36 and 37 being freely rotatable on the respective shafts 12 and 13. The gear 5 wheel 36 has a clutch face 38 thereon and the gear wheel 37 has a clutch face 39 thereon. Two clutch collars 40 and 41 are slidably keyed on the respective shafts 12 and 13. A two-arm lever 42 is pivoted on an arm 43 10 which projects from the bracket 32; the opposite ends of said two-arm lever being located at opposite sides of its pivotal connection with the arm 43 and operative to engage the respective clutch collars 40 and 41 in a 15 manner clearly shown in Figure 2. Under normal conditions as illustrated in Figure 2 the clutch collars 40 and 41 are out of engagement with the adjacent clutch faces 38 and 39 so that during a rotation of the shaft 20 23 no motion will be imparted to either of the shafts 12 or 13. If, however, the two-arm lever 42 is swung in one direction to push the clutch collar 40 into engagement with the clutch face 38 the movement of the shaft 25 23 will be imparted to the shaft 12 to rotate the same and thereby move the table 11 transversely of the base 9. On the other hand if the two-arm lever is swung in an opposite direction the clutch collar 40 will 30 be pulled out of engagement with the clutch face 38; thereby stopping the movement of the shaft 12 and will throw the clutch collar 41 into clutching engagement with the clutch face 39. The movement of the shaft 35 23 will then be imparted to the worm shaft 13 for the purpose of rotating the table 11. It is thus obvious that with my construction as just described that it is unnecessary to apply or transfer any gears when it is desired 40 to rotate either of the shafts 12 and 13 to impart either a transverse or rotatable movement to the work table. Furthermore when the two-arm lever 42 is moved into the position shown in Figure 2 both of the shafts 12 and 13 will be stopped and it is 45 an easy matter for a workman merely by pushing the two-arm lever at one side of its pivot to cause the operation of the shaft adjacent that side of the lever.

50 During the operation of a machine of this type the operator is often called from one side of the machine to the other and by the provision of the levers 27 and 28 the operator is enabled to stop or start the operation 55 of the shaft 23 at will without requiring that he walk around the base of the machine, which is generally long, in order to start or stop the movement of the shaft 23.

In order to operate and control the longitudinal movement of the table 11 along the base 9 with respect to the ram 44 I provide the following mechanism. The shaft 15 has a bevel gear 45 secured thereto which meshes with a bevel gear 46 on a short transverse shaft 47 having a bearing 48

formed by a projection of the base 9; said base being made hollow as clearly shown in cross section in Figure 2. A bevel gear 49 is secured to the shaft 47 within the base 9 and meshes with another bevel gear 50; 70 said bevel gear being secured to a sleeve 51 which is rotatably mounted in a bearing 52 in axial alignment with the shaft 14 which when rotated, as above stated, will impart a longitudinal movement to the carriage 10 75 and table 11. The shaft 14 extends freely through the gear 50 and sleeve 51 and has a clutch collar 53 slidably keyed thereon and adapted to move lengthwise on the shaft 14 to engage a clutch face 54 on the 80 bevel gear 50. A solid or core shaft 55 extends through the hollow shaft 25 and, at its opposite ends, and at opposite sides of the base 9, has hand levers 56 and 57. The hollow shaft 25 is made in sections having 85 their ends spaced apart as shown at 58 in Figure 3 and said latter ends of the shaft 25 are joined together by a yoke or bridge 59. The core shaft 55 has a clutch arm 60 secured thereto and is located within the 90 space 58; said clutch arm 60 being in operative connection with the clutch collar 53. Thus it is obvious that by a movement of either of the hand levers 56 or 57 an operator can move the clutch collar 53 into engagement with the clutch face 54 of the bevel gear 50 and the shaft 14 will be rotated.

The bracket 32 has an arm 61 which supports an index plate 62 through which passes the worm shaft 13; said index plate having divisional markings in the form of holes 63 which are adapted to be engaged by a spring pressed pin 64 carried by an arm 65 secured to the shaft 13. Thus it is possible by the registration of the pin 64 with the holes in the index plate to rotate the table 11 any predetermined distance and secure the same in the desired position by permitting the pin 64 to engage within the 105 intended indicating hole.

The rams of slotting machines are usually connected to the connecting rod and counter-weight lever by a number of separate elements which renders the cost of manufacture and assembly expensive and also requires separate fitting of the parts so that they may be connected together. In my present invention I provide a single suspension link which may be easily connected to the connecting rod, arm and counter-weight lever such for example as shown in Figures 1 and 5. The ram 44 has a slot 66 extending vertically therethrough and my improved suspension link 67 has an integral block portion 68 slidable in a guide-way 69 with respect to the height of the ram 44. The block 68 is normally held to the ram by means of a bolt 70 which is connected to the block portion 68 and has a 110 120 125 130

nut 71 for bearing against the front portion 72 of the ram. An adjusting screw 73 extends through a tapped hole 74 in the block portion 68 and upon loosening the nut 71, the ram can be moved upwardly or downwardly due to the rotation of the adjusting screw 73; said adjusting screw having no longitudinal movement relatively to the ram 44. The body portion 75 of the suspension link 67 has a cavity 76 in which fits the upper end of the connecting rod 77; it being noted that the connecting rod imparts movement in the usual manner to operate the ram. A bifurcated portion 78 projects upwardly from the body portion 75 and between the furcations is mounted the end of the counter-weight lever 79; the latter being secured between the furcations by a pivot pin 80 in similar manner. A pivot pin 81 extends through the body portion 75 and forms a pivotal connection for the top of the connecting rod 77. In this manner a single suspension link is operative to connect the connecting rod to the ram and to connect the ram with the counter-weight lever 79 and also permits of the adjustment of the ram vertically with respect to the work table. It is obvious from the foregoing description that a slotter having the features of my invention thereon can be easily operated to provide the various features and that they can be controlled from opposite sides of the base and furthermore provision is made to permit a quick operative connection for either the transverse longitudinal or rotatable movement for the work table.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

50 1. A machine of the character described including a work table; a shaft rotatable to effect a rotation of said table; a second shaft rotatable to impart an independent movement to said table; driving means normally out of driving connection with both of said shafts, and common means movable to selectively connect said driving means with either of said shafts whereby either of said shafts can be rotated.

60 2. A machine of the character described including a work table; a shaft movable to effect a rotation of said table; a second shaft movable to impart an independent movement to said table; driving means including a gear wheel; a gear wheel freely rotat-

table on each of said shafts and in mesh with said first gear wheel; clutching means secured to said shafts, said second mentioned gear wheels having clutch portions connected thereto, and a lever operatively connected to said clutching means and movable to effect movement of said clutching means into clutching engagement with said clutch portions on said second mentioned gear wheels.

3. A machine of the character described including a work table; a shaft rotatable to effect a rotation of said table; a second shaft rotatable to impart an independent movement to said table; driving means including a gear wheel; a gear wheel freely rotatable on each of said shafts and in mesh with said first gear wheel; clutch collars slidably secured to said shafts, said second mentioned gear wheels having clutch portions connected thereto, and a lever operatively connected to both of said clutch collars movable to effect movement of either of said clutch collars into clutching engagement with said clutch portions on said second mentioned gear wheels.

4. A machine of the character described including a pair of parallel shafts; a common gear for driving the shafts; clutching means on each shaft, and means for actuating the clutching means to operatively connect the gear with either of the shafts.

5. A machine of the character described including a pair of parallel shafts; a gear rotatably mounted on each shaft and having a clutch face; a common gear meshing with the gears on the shafts; a clutch collar slidably mounted on each shaft, and common means for moving either of the clutch collars into engagement with the corresponding clutch faces.

6. A machine of the character described including a pair of parallel shafts; a gear rotatably mounted on each shaft and having a clutch face; a common gear meshing with the gears on the shafts; a clutch collar slidably mounted on each shaft, and a pivotally mounted lever having its ends connected to the clutch collars for moving either clutch collar into engagement with the corresponding clutch face.

7. A machine of the character described including a ram; a suspension link adjustably secured to said ram and having two integral connecting portions; a counter-weight lever connected to one of said portions of the suspension link, and an operating connecting rod connected to the other of said connecting portions of said suspension link.

8. A machine of the character described including a ram having a slot therein and a guideway; a suspension link having a block portion slidable within said guideway; means extending through said slot and con-

necting said block portion to the ram, said suspension link having a bifurcated portion; a counter-weight lever pivotally connected between the furcations of said bifurcated portion, and a connecting rod pivotally connected to said suspension link.

9. A machine of the character described including a ram having a slot therein; a one-piece suspension link; means extending 10 through the slot and securing the link to the ram; an adjusting screw extending through the link; a counter-weight lever pivotally connected to the link, and a connecting rod pivotally connected to the link.

15. 10. A machine of the character described including a ram having a slot therein; a one-piece suspension link; means extending through the slot and connecting the link to the ram; an adjusting screw extending 20 vertically through the link; a counter-weight lever pivotally connected to the upper part of the link, and a connecting rod pivotally connected to the link.

11. A machine of the character described 25 including a ram having a slot and a guideway; a suspension link having a block portion, a bifurcated portion and a cavity, the block portion slidably fitting within the guideway; means extending through the slot 30 and connecting the block portion to the ram; a counter-weight lever pivotally connected to the bifurcated portion, and a connecting rod disposed within the cavity and pivotally connected to the suspension link.

35. 12. A machine of the character described including a ram having a slot therein and a guideway; a suspension link having a block portion, a bifurcated portion and a cavity, the block portion slidably fitting within the 40 guideway; means extending through the slot and connecting the block portion to the ram; an adjusting screw extending through the block portion; a counter-weight lever pivotally connected to the bifurcated portion, and 45 a connecting rod disposed within the cavity and pivotally connected to the suspension link.

13. A machine of the character described 50 including a base; a feed shaft; feed mechanism; clutching means for the feed shaft and feed mechanism; a transverse shaft extending through the base and having a lever at each end, and means on the transverse shaft for actuating the clutching means.

55. 14. A machine of the character described including a base; a feed shaft; feed mechanism; clutching means for the feed shaft and feed mechanism; a hollow transverse shaft extending through the base and having a 60 lever at each end; means on the transverse shaft for actuating the clutching means; a core shaft within the hollow shaft and having a lever on each end; a longitudinal feed screw; clutching means for connecting the 65 feed screw to the feed mechanism, and means

on the core shaft for actuating the last mentioned clutching means.

15. A machine of the character described including a base; a feed shaft mounted at the side of the base; a longitudinal feed screw mounted within the base; a short shaft 70 in line with the feed shaft; means for rotating the short shaft; clutching means connecting the short shaft to the feed shaft; a gear rotatably mounted on the feed screw; 75 means for operatively connecting the gear to the short shaft; clutching means for connecting the feed screw to the gear, and means at opposite sides of the base for actuating the first and second mentioned 80 clutching means.

16. A machine of the character described including a base; a feed shaft; feed mechanism mounted on the base and provided with a clutch face; a clutch collar on the feed shaft; a transverse shaft extending through the base and having a lever at each end, and a yoke on the transverse shaft for 85 moving the clutch collar into engagement with the clutch face.

17. A machine of the character described including a base; a feed shaft; feed mechanism mounted on the base and provided with clutch faces; a clutch collar on the feed shaft adapted to engage one of the clutch faces; a hollow transverse shaft extending through the base and having a lever at each end; a yoke on the transverse shaft for moving the clutch collar into engagement with one of the clutch faces; a feed screw rotatably mounted within the base; a clutch collar slidably keyed on the feed screw; a core shaft within the hollow shaft and having a lever at each end, and an arm on the core shaft for moving the last mentioned 100 clutch collar into engagement with the other clutch face.

18. A machine of the character described including a work table; a shaft rotatable to effect a rotation of said table; a second shaft rotatable to impart an independent movement to said table; a third shaft adapted to be operatively connected to either of said first shafts; a base for supporting said work table; a shaft extending transversely through said base and having hand levers thereon at opposite sides of said base; a driving clutch collar; a clutch collar slidably connected to said third shaft; automatically operated means for driving said first clutch collar, and means on said transverse shaft operative to move said second clutch collar into clutching engagement with said driving clutch collar when said transverse shaft is moved by either of said hand levers.

19. A machine of the character described including a work table; a base for supporting the work table; means for moving said work table; clutch means for effecting op-

eration of said moving means; automatically operative driving means for connection with said clutch means; a controlling shaft extending transversely of said base 5 and having hand levers connected thereto and located at opposite sides of the base, and means on said controlling shaft for effecting movement of said clutching means into connection with said driving means 10 when said controlling means is moved by either of said hand levers.

20. A machine tool comprising the combination of a bed, an upright thereon, tool supporting means on the upright, tool operating means, a saddle longitudinally slidable on the bed, a slide transversely slidable on the saddle, a work table rotatably mounted on the slide, a screw for moving the saddle longitudinally, a second screw for moving the slide transversely, a shaft extending parallel with the said second screw and operatively connected to the table for rotating the same, a second shaft extending parallel with the bed, gearing for operatively connecting the second shaft with the first named shaft and second screw, means for operating the second shaft intermittently or continuously, and means at the front of the machine 25 whereby the operator may connect either the second screw or the first shaft with the second shaft.

30. A machine of the character described including a work table; a shaft rotatable to effect a rotation of said table; a second shaft rotatable to impart an independent move-

ment to said table; a third shaft adapted to be operatively connected to either of said first shafts; a base for supporting said work table; a hollow shaft extending transversely through said base and having hand levers thereon at opposite sides of said base; a driving clutch collar; a clutch collar slidably connected to said third shaft; means on said transverse shaft operative to move said second clutch collar into clutching engagement with said driving clutch collar when said transverse shaft is moved by either of said hand levers, said hollow shaft being divided within its length to provide ends spaced apart; means connecting said ends; a longitudinal feed shaft for said table; a clutch collar slidably connected on said longitudinal feed shaft; a drive member including a clutch portion; a core shaft 55 extending through said hollow transverse shaft and having hand levers thereon located adjacent opposite sides of said base, and means secured to said core shaft between the spaced ends and operative to move 60 said latter mentioned clutch collar into engagement with said latter clutch portion, when either of said latter hand levers are moved, to effect rotation of said longitudinal feed shaft. 65

In testimony whereof I have signed my name to this specification in the presence of two subscribing witnesses.

FRANK S. JONES.
